UNITED STATES PATENT OFFICE.

KARL BÖTTCHER AND FRIEDRICH HEYM, OF BENRATH, NEAR DÜSSELDORF, GERMANY.

AUTOMATIC GRASPER.

No. 813,786.

Specification of Letters Patent.

Patented April 24, 1906.

Application filed February 12, 1905. Serial No. 300,637.

To all whom it may concern:

Be it known that we, KARL BÖTTCHER and FRIEDRICH HEYM, subjects of the King of Prussia, German Emperor, and residents of Benrath, near Düsseldorf, in the Province of the Rhine, German Empire, have jointly invented certain new and useful Improvements in Automatic Graspers, of which the following is an exact specification:

Our invention relates to automatic graspers for lifting or hoisting coarse goods, as ores and the like. According to our invention in such graspers shovels are provided, swinging by means of knee-levers around an axle, and are suspended from specific governing-rods. Thus the shovels are intended continuously to slide with increasing power below the goods to be hoisted, when closure of the shovels takes place. In such graspers one has hitherto employed for closing the shovels a set of pulleys arranged horizontally, thereby obtaining a constant power for closing the shovels. Furthermore, by such an arrangement of the set of pulleys a drawback encounters in that the rope when taken from the horizontal pulleys to the pulleys leading the rope upward is bent off in a direction different from the first one, whereby the wearing of the rope is promoted. A further drawback encounters thereby that the horizontally-arranged parts of the rope lying immediately above the goods when the grasper is opened come in contact with the rough goods. A quicker wearing of the rope is caused thereby, owing to the horizontal arrangement of the set of pulleys. The closing power shows almost the same magnitude during the closure of the shovels and the latter thereby are often not in the position to crush the pieces being between the shovels, and then the automatic grasper has been put in motion without being closed. These drawbacks are avoided by the present invention, and a convenient constructional form of an automatic grasper is illustrated in the following figures, in which—

Figure 1 is a side elevation of a closed grasper. Fig. 2 is a side elevation of the grasper completely opened.

In the drawings similar letters denote similar parts.

a a are the shovels, and *b b* are knee-levers, being pivotally connected with their one end to the outer edges of the shovels.

c c are governing-levers pivotally secured at the inner end of the shovels and carrying the same. The knee-levers *b b* are rotatably mounted on the governing-levers *c c* and are fixed with their other end to the movable axle *e'*, carrying the pulleys *d*.

e' is a stationary axle from which the governing-levers *c c* are suspended and upon which the pulleys *d'* are mounted.

f is a cross-head carried by the axle *e'*.

Around the pulleys *d d'* the rope *g* for opening and closing the shovels is wound, the ends of which are secured at the cross-head *f*. The latter compensates, furthermore, unequal dilatations of the rope. The rope is taken upward to a gearing arrangement (not shown), for operating the set of pulleys.

g' is a link at both ends of the axle *e'* and carried thereby. The link *g'* is provided with a slot *g²*, in which the axle *e'* of the movable pulleys *d'* moves up and down. The links *g'* project with their parts *g³* over the axle *e'* and carry shells *h h* for guiding the rope *g*.

The construction as foregoing described operates in the following manner: After the grasper is lowered till it has reached the goods to be lifted the shovels *a* are opened by winding off the rope *g*, thereby permitting the pulleys *d* to be lowered in the slot *g²* and to rotate the levers *b b* around the pins *e e*. The opening of the shovels is limited by the slot *g²*. In order to seize the goods automatically by the shovels, then the pulleys *d* must be moved upwardly by winding up the rope *g*. The locking power at the beginning of the closure is about equal to that exerted by the set of pulleys. Owing to the arrangement of the knee-levers *b b*, the closing power is gradually increased till its highest amount, when the inner lever parts of the knee-levers *b b* are almost horizontal. The slot *g²* prevents the knee-levers *b b* from being crushed if the shovels are closed.

The arrangement can be modified by mounting the cross-head *f* on the axle *e*. The links *g'* can be secured at the axle *e'*, and the slot *g²* can be arranged in the upper part of the links for guiding the upper axle *e'*.

Having thus fully described the nature of our invention, what we desire to secure by Letters Patent of the United States is—

An automatic grasper comprising in combination shovels, knee-levers pivotally con-

nnected, at their one end with the outer edge of the said shovels, governing-levers rotatably carrying said knee-levers and pivotally secured to the inner edge of the shovels, stationary pulleys, a stationary axle upon which said stationary pulleys and said governing levers are mounted, movable pulleys, a movable axle carrying said movable pulleys and being connected with the other ends of said knee-levers, a rope wound around the mov-

able and stationary pulleys and links carried by said stationary axle and provided with a slot engaging said movable axle.

In witness whereof we have hereunto signed our names in the presence of two witnesses. 15

KARL BÖTTCHER,
FRIEDRICH HEYM.
